UNITED STATES PATENT OFFICE.

JOSEPH T. SIMPSON, OF CHICAGO, ILLINOIS.

OVERSHOE.

1,111,188.

Specification of Letters Patent. Patented Sept. 22, 1914.

Application filed May 19, 1913. Serial No. 768,506.

To all whom it may concern:

Be it known that I, JOSEPH T. SIMPSON, a citizen of the United States of America, and a resident of Chicago, county of Cook, and State of Illinois, have invented certain new and useful Improvements in Overshoes, of which the following is a specification.

My invention relates to overshoes and has for its object improvements which tend to hold the shoe in place when worn.

In the accompanying drawings—Figure 1 is a side elevation, partly in section, of a rubber over shoe; Fig. 2 is a section on line 2—2 of Fig. 1; and Fig. 3 is a rear elevation 15 of the metallic reinforcing strip.

The over shoe 10 is shown in position on an ordinary walking shoe 11. One of the objectionable features of an ordinary "rubber" is that, when walking in mud, the overshoes frequently slip at the heel and come off. I overcome this objectionable feature by inserting in the heel part of the overshoe a properly shaped piece of spring steel 12 which extends from the part of the overshoe 20 under the heel of the walking shoe to the upper part of the overshoe in the rear center. This spring steel is so shaped that its initial tension will produce a light inward pressure at the upper edge of the overshoe, and is of such stiffness as to require 25 rather more than the ordinary force to remove the overshoe. To provide sufficient strength to withstand long usage, and to reduce the liability of the strip 12 being bent far enough to give it a set other than that intended, I add a short reinforcing strip 13 to the main reinforcing strip 12. This secondary strip is placed at the bend where

the horizontal and vertical parts of the strip 12 join each other. This secondary strip is 40 shown as a separate piece of spring steel riveted to the main strip, but I may, of course, make it integral therewith.

What I claim is:—

1. The combination with an overshoe, of a 45 reinforcing strip of spring metal completely embedded in the walls of the heel of said overshoe, said strip comprising two portions bent at substantially right angles to each other, one of said portions being located in 50 the tread portion of said heel and extending throughout the length thereof and the other of said portions being located in the rear upright wall of said heel midway between the sides thereof and extending throughout the 55 height of said wall.

2. The combination with a rubber over- 60 shoe, of a strip of spring metal completely embedded in the rubber walls of said over- shoe, said strip comprising two portions bent 65 at substantially right angles, one of said portions being located in the tread portion of the heel and extending throughout the length thereof and the other of said portions in the rear upright wall of the heel 70 midway between the sides thereof and ex- tending throughout the height of the wall, and a second reinforcing strip at the corner where the main strip bends from the horizontal to the vertical.

Signed at Chicago, Illinois this 15th day of May 1913.

JOSEPH T. SIMPSON.
